UNITED STATES PATENT OFFICE

JOSEPH F. SCHMIDT, OF RAILROAD, PENNSYLVANIA, ASSIGNOR TO WHEELER COMPANY, OF RAILROAD, PENNSYLVANIA, A CORPORATION OF PENNSYLVANIA

PRESS

Application filed November 5, 1927. Serial No. 231,208.

This invention relates to presses, and more particularly to a semi-automatic press of the hydraulic type adapted for forming articles from plastic compositions.

5 The present types of presses embody a stationary base in which the mold cavity is formed and an upper vertically reciprocable plunger the lower end of which forms the top of the mold. The plunger is operable by hydraulic pressure, and the actuation of the plunger is controlled by an operator seated at the front of the apparatus. The operator referred to also controls a lower plunger the upper end of which forms the 10 bottom of the mold, and which is adapted to be moved upwardly to eject finished articles from the mold. The material from which the articles are formed is weighed manually by a second operator seated at the opposite 15 side of the machine, and is manually poured into the mold cavity after the previously formed article has been ejected and before the upper plunger is moved downwardly. Thus it will be apparent that two operators 20 are required for forming the articles by each hydraulic press.

The material usually employed in making the articles is in a loose semi-plastic condition and contains a considerable portion of 25 air. The valve controlled by the operator for actuating the plungers is adapted to be moved to operative position to cause the plunger to impact against the material in the mold, to a neutral position, and to an 30 inoperative position wherein the pressure is released from the plunger. Owing to the inherent nature of the material above referred to, it is the common practice initially to turn the pressure control valve to operative 35 position momentarily to impact the plunger against the material, and then to turn the valve to neutral position to hold the plunger down, these actions resulting in forcing the air in the body of material to escape therefrom. After reaching the neutral 40 position, the valve is then alternately moved from operative to inoperative position to deliver a series of impacts to the material in the mold to properly compress it. 45 After the compressing action is completed,

the control valve is moved to inoperative position and permitted to remain in such position, whereupon the plunger is elevated to inoperative position by coil springs provided for this purpose. The operator at the 55 front of the apparatus then depresses a pedal or other lever to elevate the lower plunger and thus eject the finished article from the mold. The ejector is then withdrawn into the mold whereupon the operator at the rear of the apparatus again pours into the mold the material which has been measured or weighed during the molding operation.

An important object of the present invention is to provide a molding press of the 60 hydraulic or other mechanically operated type wherein the measuring of the material is adapted to be done by the operator who controls the hydraulic valve, thus dispensing with the necessity of a second operator.

A further object is to provide manually controlled means operable by the single operator referred to for receiving from a suitable hopper and transmitting to the mold the correct quantity of material to form each successive article.

A further object is to provide a manually controlled material measuring device adapted to be moved to a position beneath a material hopper and to a position over the mold, 80 and to provide valves beneath the hopper and beneath the measuring device and automatically operable by movement of the measuring device to permit material to flow downwardly into the measuring device when it 85 is arranged beneath the hopper and to permit the material to be discharged into the mold when the measuring device is arranged thereover.

A further object is to provide means as- 90 sociated with the measuring device for varying the capacity thereof according to the physical characteristics of the material and varying uses of articles to be molded.

A further object is to provide a hydraulic 95 control valve operable by one hand of the operator, and associated locking means for the valve handle operable by the other hand of the operator, thus requiring the use of two hands when the plunger is to be actuated to 100

prevent the possibility of injury to the operator.

A further object is to provide novel means operable by upward movement of the pressure plunger after an article has been formed for ejecting the article from the mold.

A further object is to provide depending means connected to and movable with the pressure plunger and having a portion adapted upon upward movement to engage beneath a portion of the ejecting plunger to elevate the latter when the pressure plunger is moved upwardly toward inoperative position.

15 Other objects and advantages of the invention will become apparent during the course of the following description.

In the drawings I have shown one embodiment of the invention. In this showing,

20 Figure 1 is a front elevation of the apparatus,

Figure 2 is a side elevation of the same, Figure 3 is a section taken substantially on line 3—3 of Figure 1, parts being omitted,

25 Figure 4 is an enlarged side elevation of a portion of the apparatus,

Figure 5 is a detail perspective of the hopper valve,

30 Figure 6 is an enlarged front elevation of a portion of the apparatus,

Figure 7 is a detail perspective of the carriage including the measuring device,

Figure 8 is a vertical sectional view on line 8—8 of Figure 3,

35 Figure 9 is a section on line 9—9 of Figure 8,

Figure 10 is an enlarged vertical sectional view through the valve casing,

Figure 11 is a plan view of the same,

Figure 13 is an enlarged front elevation of the lower portion of the apparatus,

Figure 14 is a side elevation of the same,

45 and,

Figure 15 is an enlarged detail sectional view showing the safety handle locking means.

Referring generally to Figures 1 and 2,

50 the numeral 10 designates a pair of side supports at the upper ends of which is mounted a bed plate 11 carrying a mold 12 of the usual type having a mold cavity 13 therein in which the desired articles are adapted to

55 be formed. This mold is provided with an ejector plunger 14 the upper extremity of which is arranged in the mold in the usual manner and forms the bottom thereof. A crosshead 15 is carried by the plunger beneath a guide 16 depending from the mold bed.

60 A coil spring 17 is arranged between the crosshead 15 and the guide 16 to project the plunger downwardly to normal position.

A pair of links 18 are pivotally connected at 65 their upper ends to the crosshead 15 and

at their lower ends to the inner end of an arm 19 carried by a shaft 20. This shaft is journaled in bearings 21 carried by the supports 10, and may, if desired, be provided with a manually operable handle 22. It will be apparent that outward movement of the handle is adapted to rock the shaft 20 about its axis to swing the arm 19 upwardly and thus lift the plunger 14, but it is preferred that automatic means to be described be employed for ejecting the finished articles. A plurality of square rectangularly arranged posts 23 are secured at their lower ends to the bed 11 and project upwardly thereabove for a substantial distance as shown in Figures 1 and 2. These posts are adapted to support a crosshead 24 for vertical reciprocation, and the bottom of the crosshead is provided with an impacting member 25 which is movable downwardly into the mold cavity in a manner to be described. The lower face of the impacting member forms the top of the mold, as will be apparent, to determine the shape of the upper end of the articles being formed. The crosshead 24 is connected to a plunger 26, the upper end of which carries a piston (not shown) reciprocable in a pressure cylinder 27. The cylinder is provided with an outstanding base portion 28 which is secured to the upper ends of the posts 23 by nuts 29. A pair of rods 30 are slideable in suitable openings formed in the base 28 and are secured at their lower ends to the crosshead 24 in the usual manner. Coil springs 31 are arranged between the base 28 and upper adjustable heads 32 carried by the rods 30 and accordingly it will be apparent that the springs 31 are operable to normally project the crosshead 24 upwardly.

Means are provided for actuating the crosshead 24 to effect compression of material in the mold cavity and to release the crosshead for upward movement. Referring to Figures 10 and 11 the numeral 33 designates a valve casing having an outlet passage 34 connected by a conduit 35 to the upper end of the cylinder 27, as shown in Figure 1. Oil is preferably employed as the hydraulic medium and is supplied to the casing 33 through an inlet port 36, this port being connected to a suitable pressure supply pipe 37 provided with a manually controlled valve 38. The port 36 communicates with a chamber 39 formed in the casing 33 and a valve plug 40 is arranged in this chamber and provided at its upper end with a valve seat 41. A valve 42 engages this seat and is carried by a stem 43. The lower end of the valve stem is slideable in an opening 44 formed in the plug 40, while the upper end of the stem is slideable in an opening 45 formed in a plug 46, the valve normally being projected downwardly to closed position by a coil spring 47 arranged in the opening 45. The opening 44 in the plug 40 com-

municates with a lower opening 48, which in turn, communicates with a transverse passage 49 formed in the valve casing. The passage 49 is preferably drilled into the side of the valve casing and the outer end of the passage is closed by a plug 50.

The inner end of the passage 49 communicates with a vertical passage 51 which is also drilled in the valve casing and is closed at its upper end by a plug 52. The passage 54 is drilled inwardly to communicate with the passage 51 as shown in Figure 10, and passes through a chamber 53. A ring, 54 is arranged in the lower portion of this chamber and receives a plug 55 the upper end of which is provided with a valve seat 56. A valve 57 engages this seat and is formed on a stem 58 the upper end of which is vertically reciprocable in an opening 59 formed in a plug 60 threaded in the casing 33. The lower end of the valve stem 58 reciprocates in an axial opening 61 formed in the plug 55. An exhaust port 62 is formed in the casing 33 and communicates with the lower portion of the chamber 53 beneath the plug 55, and fluid pressure from the passage 34 is adapted to escape through the port 62 around the stem of the valve 57 when the latter is lifted. The port 62 is connected with the pipe 62' to transmit pressure fluid thereto. The valve 57 is normally retained on its seat by a suitable coil spring 63 arranged in the opening 59. The inlet and exhaust valves 42 and 57 are adapted to be actuated by operating stems 64 and 65 respectively, each of these stems being arranged beneath and in axial alignment with its corresponding valve stem. Each of the stems 64 and 65 forms a part of a plunger 66 which is mounted to reciprocate in a guide plug 67 threaded in the casing 33, and packing washers 68 surround the valve actuating stems to prevent leakage of pressure as will be apparent.

Depending arms 69 are arranged on opposite sides of the casing 33 and support a rocker 70. This rocker is provided with oppositely extending arms 71 arranged beneath the plungers 66, and each arm is provided with a screw 72 extending upwardly therethrough and adapted to be secured against movement by lock nuts 73. It will be apparent that the screws 72 are adapted to be adjusted vertically to vary the amount of opening of the valves 42 and 57 for any given movement of the rocker. The rocker 70 is provided with an operating arm 74 to the end of which is connected a link 75. The valve casing is provided with a bearing 76 receiving a shaft 77, the rear end of this shaft being provided with an eccentric 78 receiving the upper end of the link 75. The forward or outer end of the shaft 77 is polygonal as indicated at 79 (see Figure 12) to receive the hub 80 of a handle 81.

The hub 80 is provided with a stop 80' adapted to engage the head of a screw 81' carried by the valve casing to limit the turning movement of the handle 81.

A support indicated as a whole by the numeral 82 is arranged above the bed 11 to the rear thereof, as shown in Figures 3, 4 and 8. This support includes opposite outstanding arms 83 which are extended forwardly for connection to the two rear posts 23. Caps 84 are provided for the ends of the arms 83 and are secured thereto by screws 85. The arms may be ribbed as at 86 for the purpose of reinforcement, as will be apparent. The support 82 is provided with a central solid portion 87 which is relatively long, as shown in Figures 3 and 8. Beneath and adjacent the outer edges of the central portion 87, the support is provided with depending portions 88 having annular faces recessed as at 89 to form sockets for the reception of one corner portion of each of a pair of preferably square guide rods 90. Screws 91 are adapted to secure the guide rods in position.

A hopper 92 is arranged over the support 82 and is provided with a depending discharge spout 92 extending through an opening 94 formed in the central portion 87 of the support. A gate or valve 95 is slidable under the lower end of the spout 93 to form a closure therefor. The lower face of the central portion of the support is recessed as at 96 to slidably receive the gate 95 and guide plates 97 are adapted to support the gate for reciprocating movement. These guides may be secured in position by screws 98. The rear end of the gate 95 is secured to a slidable operating plate 99 by a screw 100, as shown in Figure 8. The plate 99 is provided with a longitudinal slot 101 through which extends an integral depending member 102 carried by the top 87 of the support 82. The purpose of the depending member 102 will be referred to later. The rear end of the plate 99 is secured by rivets or the like 103 to a rod 104 which extends through a guide opening 105 formed in a depending member 106 carried by the rear end of the central portion of the support 82. A coil spring 107 surrounds the rod 104, the spring contacting at its rear end with the depending member 106 and at its forward end with a collar 108 surrounding the rod 104. It will be apparent that the spring 107 normally projects the rod 104 forwardly to close the gate 95.

A carriage indicated as a whole by the numeral 109 is slidable on the guide rods 90. The carriage is shown in detail in Figure 7 of the drawings and includes longitudinally extending spaced side portions 110 arranged on opposite sides of the depending member 102. The edge portions of the carriage 109 are provided with spaced guide members 111

which are angular in form to slidably receive the inner corner portions of the guides 90. The rear ends of the side members 110 are connected by a solid cross member 112 in which is threaded a screw 113 adapted to limit forward movement of the carriage. An abutment 113 adjacent the opposite ends of the side members 110 is adapted to contact with the depending member 102, as shown in Figure 8, to limit rearward movement of the carriage. The forward portion of the carriage is provided in its lower face with a laterally extending cut out portion 114 connected at its inner end to a vertically extending recess 115 for a purpose to be described. The forward end of the carriage is provided with a measuring device indicated as a whole by the numeral 116, the rear edge 117 of this device projecting upwardly a slight distance above the upper face of the carriage to contact with the forward edge of the gate 95 to move the latter rearwardly.

The measuring device 116 preferably is provided with a cast integral body having a vertical slot 118 extending rearwardly therein, the rear end of the slot being substantially semi-cylindrical as shown in Figure 7. A block 119 is slideable forwardly and rearwardly in the slot 118 and is provided with a rear semi-cylindrical face coacting with the curved rear end of the slot 118 to form a material measuring pocket 120. A plate 121 is arranged against the forward face of the body of the measuring device and forms a closure for the slot 118. Screws 122 pass through the plate 121 and the side portions of the body of the measuring device and are threaded at their rear ends in the forward end of the body of the carriage 109. It will be apparent that these screws secure the measuring device to the body of the carriage.

The forward face of the block 119 is provided with an undercut slot 123 receiving a head 124 of a screw 125, this screw being threaded through the plate 121. An operating knob 126 is carried by the screw 125 and is provided with an outer knurled portion 127. The inner end of the knob is provided with a milled annular flange 128 adapted to be engaged by one end of a leaf spring 129, the opposite end of this spring being secured to the plate 121 by a screw or the like 130.

A gate 131 is arranged beneath the measuring device to form a closure for the bottom of the pocket 120. Opposite edges of the gate 131 are provided with spacing strips 132 and guide strips 133 are arranged over the spacing strips. The guide and spacing strips are secured to the gate 131 by rivets or the like 134. The inner edges of the guide strips extend inwardly beyond the spacing strips for slidable engagement in longitudinal slots 135 formed in the sides of the body of the measuring device. The gate 131 is provided with a substantially circular opening 136 which is

adapted to be arranged beneath the pocket 120 to discharge material therefrom. The rear end of the gate 131 is secured to a rearwardly extending rod 137, and this rod passes through an opening 138 formed in the lower end of the depending member 102. Forward and rear collars 140 are carried by the rods 137 and are adapted to engage opposite sides of the depending member 102 to effect movement of the gate 131 to open and closed positions in a manner to be described.

The end portion of one of the arms 83, preferably the arm at the right hand side of the apparatus, is provided with an upwardly and rearwardly extending preferably integral bearing arm 141 as shown in Figures 3 and 9. A lever arm 142 is pivotally supported intermediate its ends upon the bearing 141 by a bolt 143, the latter preferably being provided with an oil cup 144 or other lubricating means. The inner end 145 of the lever extends into the cut out portion 114 of the carriage 109 and is provided with a roller 146 engaging in the elongated opening 115. The forward end 147 of the operating lever extends through a slot 148 formed in an arcuate plate 149, this plate being secured against the rear face of one of the posts 23 by screws 150 passing through a plate 151 arranged against the forward face of the post. The outer extremity of the lever is provided with an operating handle 152 to which a latch operating member 153 is pivotally connected as at 154. A spring 155 is arranged between the handle 152 and the member 153 to normally retain the latter in the position shown in Figure 3. A locking pin 156 is pivotally connected to the latch operating member as at 157 and is adapted to engage in an opening 158 formed in the inner end of the plate 149. The latch pin operates in a guide 159 carried by the operating lever, and the latter is adapted to engage against a stop 160 to limit its inward movement with the latch pin in alignment with the opening 158.

A pair of depending rods 161 is pivotally connected to the head 24 as at 162, the rods being arranged outwardly of the head as shown. The lower ends of these rods extend downwardly beneath the head 24 and are connected to a transverse bar 163 as shown in Figure 14. The rods preferably extend downwardly through suitable openings formed in the upper ends of the supports 10 and bed 11. It will be apparent that the bar is adapted to reciprocate vertically with the pressure head 24. A pair of rods 164 are carried by collars 165 mounted on the shaft 20. Springs 166 surround the rods 164 between the collars thereof and the bar 163. The rods 164 extend through relatively large openings in the bar 163 and it will be apparent that the springs tend to urge the bar rearwardly for a purpose to be described.

The cross bar 163 is adapted to slidably engage a pair of depending bars 167 secured at their upper ends to the support 10 as at 168. The lower ends of the bars 167 are relatively restricted in width and join the wider upper portions thereof in an upwardly and outwardly curving face 169. The forward edges of the upper or wider portions of the bars 167 are arranged flush with the outer 5 extremity of the cross-head 15, as shown in Figure 14. It will be apparent that the bar 163 is adapted to move downwardly without affecting the crosshead 15, but is adapted to engage therebeneath upon upward movement 10 to cause the crosshead and the plunger 14 to move upwardly.

Means are provided to cause the left hand of the operator to be occupied before he can operate the valve handle 81 to supply fluid 20 pressure to the cylinder 27. Referring to Figure 13 the numeral 170 designates a transverse rod pivotally connected at one end as at 171 to the valve lever 81. The opposite end of this rod is slidable in openings 25 172 formed in arms 173 of a plate 174. A safety handle 175 is pivotally connected to the lower end of the plate 174 as at 176 and the lower portion of the handle is normally arranged between the ears 173 thus preventing 30 given inward movement of the end of the rod 170, and consequently preventing movement of the valve handle 81. The upper portion of the handle 175 is provided with a rearwardly extending rod 177 35 rounded by a coil spring 178, the rear end of the spring being secured to the rod 177 while the forward end contacts with the rear face of the plate 174. It will be apparent that the operator is free to move the handle 40 81 to the left only when he grasps the upper end of the handle 175 and pulls it outwardly.

The operation of the device is as follows:

With the operating lever 142 and elements actuated thereby arranged in the positions 45 shown, the operator may grasp the handle 152 and member 153 and move these elements toward each other to release the pin 156 from the opening 158. The outer end of the lever is then swung outwardly and it will be apparent 50 that the arrangement of the roller 146 in the opening 115 will cause the carriage to move forwardly. The use of the roller materially reduces friction to permit the apparatus described more easily to be operated. 55 It will be apparent that the pocket 120 will have received a charge of material from the hopper, the quantity of material corresponding to the amount necessary for the particular articles to be molded. Rotation of the 60 knob 126 against the action of the spring 129 causes the plug 119 to be moved inwardly or outwardly to vary the quantity of material which the opening 120 is adapted to receive according to the requirements of the mold. 65 The spring 129 is adapted to prevent acci-

dental turning of the knob 126. As the carriage moves forwardly, it will be apparent that the spring 107 will project the gate 95 forwardly to close the lower end of the spout 93. The forward action of the carriage continues until the opening 136 in the valve 131 reaches a point in alinement with the mold cavity 13, at which time the collar 140 will contact with the depending member 102 to limit further forward movement of the rod 137. Thus further forward movement of the valve or gate 131 will be prevented and the carriage will continue to move forwardly until the opening 120 is arranged over the opening 136, and above the mold cavity 13, 70 whereupon the material in the measuring device will flow downwardly thereinto. The operator then swings the handle 152 back to its normal position and releases the member 153 to permit the pin 156 again to enter its opening 158. At this point, the material will have been placed in the mold and the molding operation is ready to take place. The operator then grasps the upper end of the handle 175, shown in Figures 13 and 14, 75 and moves this element outwardly whereupon the valve handle 81 may be moved to the left. This action causes the link 75 to be elevated from the neutral position shown in Figure 10, thus moving the plunger 66 upwardly to 80 cause the pin 64 to raise the valve 42, fluid pressure thereupon flowing through the opening 44, passages 49, 51 and 34, and through pipe 35 to the cylinder 27 to effect downward movement of the plunger. As soon as the 85 plunger has completed its downward movement and is impacted against the material in the mold, the valve handle is returned to neutral position momentarily while air escapes from the material in the mold. The intake 90 valve 42 is again opened to deliver a second impact to the material and the valve handle is then swung to exhausting position momentarily, thus closing the valve 42 and opening the valve 57 to permit the pressure 95 fluid to escape through pipe 35, passages 34, openings 61 and port 62, back to the source of supply. This action permits the springs 31 to slightly raise the head 24, and the valve action is repeated several times, the handle 100 115 120 125 130 135 140 145 150 155 160 165 170 175 180 185 190 195 200 outer extremity of the crosshead 15 and accordingly when the head 24 moves downwardly the bar 163 slides freely over the crosshead and then snaps inwardly against edges of the narrow lower portions of the bars 167, the entire downward movement of the crosshead being accomplished without effecting any movement of the plunger 14. When the head is released for upward movement in the manner previously stated, the rods 161 will be moved upwardly together with the bar 163, whereupon the latter will engage beneath the crosshead 15 and effect upward movement of the plunger 14 against the tension of the spring 17. This action causes the plunger to lift the finished article from the mold, thus permitting its removal. As soon as the bar 163 reaches the curved face 169 in its upward movement it will be moved outwardly against the tension of the springs 166 until it reaches the wider portions of the bars 167, whereupon the crosshead will be released from the bar 163 and will be moved downwardly to normal position by its spring 17.

From the foregoing it will be apparent that the structure disclosed provides a press which is adapted to be controlled wholly by a single operator, and since the operator must use both hands to swing the valve handle 81, it is apparent that injury to his hands upon downward movement of the plunger is prevented. It also will be apparent that the apparatus is adapted to function automatically so far as the ejecting of the finished articles is concerned, whereby the operator is permitted to remove the finished article from the top of the mold at substantially the same time the operation of the lever 142 is started to deliver a new charge of material to the mold. So far as the valves of the hopper and measuring device are concerned, these elements are adapted to operate automatically upon movement of the carriage from receiving to discharging positions.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. In an apparatus of the character described, a mold having a section movable to compress material in the mold, a material hopper, a measuring device movable to a position beneath said hopper to receive material therefrom and to a position over said mold to discharge material thereinto, manual means for effecting movement of said measuring device, and means for locking said manual means in a position with said meas-

uring device removed from proximity to said mold.

2. In an apparatus of the character described, a mold having a section movable to compress material in the mold, a material hopper, a measuring device movable to a position beneath said hopper to receive material therefrom and to a position over said mold to discharge material thereinto, a manually operable lever for effecting movement of said measuring device, and latch means for locking said lever in a position with said measuring device removed from proximity to said mold.

3. In an apparatus of the character described, a mold having a section movable to compress material in the mold, a material hopper arranged above and to one side of said mold, guides arranged between said hopper and said mold, a measuring device slidably supported by said guides, said measuring device being movable to a position beneath said hopper to receive material therefrom and to a position over said mold to discharge material thereinto, a manually operable lever pivotally supported intermediate its ends and connected at one end to said measuring device, and means for locking said lever in a position with said measuring device beneath said hopper.

4. In an apparatus of the character described, a mold having a section movable to compress material in the mold, a material hopper arranged to one side of said mold and provided with a lower discharge opening, a slidable gate normally closing said opening, a material measuring device movable to a position beneath said opening to contact with and open said gate and receive material from said hopper, said measuring device having a vertical opening therethrough, a slidable gate normally closing said last named opening, said measuring device being movable to arrange the opening therein directly over said mold, means adapted to effect the opening of said last named gate as said measuring device assumes said last named position, a manually operable lever for effecting movement of said measuring device, and manually operable means for locking said lever in a position with said measuring device arranged beneath the opening in said hopper.

5. In an apparatus of the character described, a mold having a section movable to compress material in the mold, a material hopper arranged to one side of said mold and provided with a lower discharge opening, a slidable gate normally closing said opening, a material measuring device movable to a position beneath said opening to contact with and open said gate and receive material from said hopper, said measuring device having a vertical opening therethrough, a slid able gate normally closing said last named opening, said measuring device being mov-

able to arrange the opening therein directly over said mold, means adapted to effect the opening of said last named gate as said measuring device assumes said last named position, and guides slidably supporting said measuring device for movement between said hopper and said mold, a manually operable lever for effecting movement of said measuring device, and manually operable means 5 for locking said lever in position with said measuring device arranged beneath said hopper.

6. In an apparatus of the character described, a mold having a section movable to 15 compress material in the mold, a material hopper arranged to one side of said mold and provided with a lower discharge opening, a slideable gate normally closing said opening, a material measuring device movable to a position 20 beneath said opening to contact with and open said gate and receive material from said hopper, said measuring device having a vertical opening therethrough, a slideable gate normally closing said last named opening, 25 said measuring device being movable to arrange the opening therein directly over said mold, means adapted to effect the opening of said last named gate as said measuring device assumes said last named position, a pair of 30 stationary horizontal guides, a carriage slidably mounted between said guides and provided with a recess, said measuring device being secured to said carriage, a manually operable lever, and a roller carried by said 35 lever and mounted in said recess to effect movement of said measuring device upon operation of said lever.

7. In an apparatus of the character described, a mold having a movable section 40 adapted to compress material therein, a plurality of upstanding posts slidably supporting said movable section, a support including a central portion and a pair of arms secured to certain of said posts, a hopper supported 45 by the central portion of said support, a pair of spaced guides carried by said support, a carriage slidably supported by said guides, a material measuring device carried by said carriage, said measuring device being movable 50 to a position beneath said hopper to receive material therefrom and to a position over said mold to discharge material thereinto, a manually operable lever pivotally supported intermediate its ends, said carriage being provided with a recess, and a roller carried by one end of said lever and operative in said recess for effecting movement of said carriage upon movement of said lever.

8. In an apparatus of the character described, a mold having a movable section 55 adapted to compress material therein, a plurality of upstanding posts slidably supporting said movable section, a support including a central portion and a pair of arms secured

to certain of said posts, a hopper supported by the central portion of said support, a pair of spaced guides carried by said support, a carriage slidably supported by said guides, a material measuring device carried by said carriage, said measuring device being movable to a position beneath said hopper to receive material therefrom and to a position over said mold to discharge material thereinto, a lever having one end engaging said carriage and operative for effecting movement thereof, and latch means for locking said lever against movement with said measuring device arranged beneath said hopper.

9. In an apparatus of the character described, a member having a mold cavity therein, a lower plunger projecting from the bottom of said member, an upper plunger movable downwardly into said cavity to compress material therein, a crosshead movable with said upper plunger, a projecting member carried by said lower plunger, a cross bar connected to said crosshead to move therewith and adapted to engage beneath said projecting member to lift said lower plunger 85 when said crosshead is elevated, and means for retaining said cross bar out of engagement with said projecting member during downward movement of said crosshead.

10. In an apparatus of the character described, a member having a mold cavity therein, a lower plunger projecting from the bottom of said member, an upper plunger movable downwardly into said cavity to compress material therein, a crosshead movable with said upper plunger, a projecting member carried by said lower plunger, a cross bar connected to said crosshead to move therewith and adapted to engage beneath said projecting member to lift said lower plunger 100 when said crosshead is elevated, a pair of bars against which said cross bar is adapted to slide vertically, said pair of bars being provided with undercut lower portions to permit said cross bar to move to a position beneath said projecting member, and resilient means for retaining said cross bar against said pair of bars.

In testimony whereof I affix my signature.

JOSEPH F. SCHMIDT.
